James A. Franklin

5775X

Letters Patent.

The schedule referred to in these letters Patent and making part of the same, containing a description of the work of the said James A. Franklin, himself of his improvement in the Cast Iron plough-share,

The advantage which the plough-share claims over those now in use, consists of being modeled so as to have two points and two edges, the one of which may be used after the other is worn out, by changing its position on the mould board which being so constructed as to admit of the share being reversed, or changed, one end for the other at pleasure, it answers the purpose intended. The share is so made and constructed, as to have the two different edges, when reversed, present the same shape & structure. The share is made of cast iron or other firm and durable substance, & the mould board is also to be made of cast iron, or other firm & durable substance. The share is separate & distinct from the mould board; & the manner of fastening it to the mould board is by having two sockets, or mortises in or near the centre of the share, which are adapted to fit to two points or tenons on the mould board, in the place or groove where the said share fit; the said share being so placed on the mould board, as to admit of a cap or confiner to cover one point & edge or one half of the share; the said cap or confiner then extends an equal distance on the mould board & presents a plain and smooth surface. The cap and confiner is then fastened to the mould board by two strong and sufficient screws, or一枚 each which go through the thickness of the cap, or confiner so as to be strong, firm and lasting. When one edge of the share is worn out, thereby

turning it round so as to present the reverse edge and point of support alternately with the other, so that it may not turn, & the hole being kept round, so as to be impervious with the needle, so that the needle cannot work the same firmly by means of the head cap or confine, with the needles not turning or breaking, & from 9 turns which all combined make it strong & durable, — The needle board is so formed as to take the one half of the share into a groove or place underneath the needle board, for one of the purposes of the cap or confine likewise, Thus the impervious share, was the purpose of two common shares & will cost no more than one on the ordinary plan now in use.

For a further illustration of my improvement I refer to the drawing & model of the same deposited in the Patent office. What I claim as my invention or improvement which I wish to secure by Letters Patent, is the improvement in the ordinary plough share, as above described, the share having two points and two edges which may be receded at pleasure thereby serving the purposes of two common shares & costing no more than one of the ordinary kind, I claim also the mode of fastening the share to the mould board as before described.

Witness,

James. D. &
L. Beck

James. A. Coulter
